UNITED STATES PATENT OFFICE.

CHARLES G. HORNUNG, OF BUFFALO, NEW YORK, ASSIGNOR TO LARKIN CO., OF BUFFALO, NEW YORK.

BOX OR CONTAINER.

1,376,939.

Specification of Letters Patent.

Patented May 3, 1921.

Application filed April 6, 1920. Serial No. 371,597.

To all whom it may concern:

Be it known that I, CHARLES G. HORNUNG, a citizen of the United States, residing at Buffalo, in the county of Erie and State of New York, have invented a new and useful Improvement in Boxes or Containers, of which the following is a specification.

This invention relates to boxes or containers usually made of sheet metal and used in connection with shoe polish, stove polish and other materials.

The objects of this invention are to provide a box of this kind of improved construction, which is so made that it can be readily opened; also to provide a box of this kind which is so made that the cover will form a tight connection with the body portion of the box so as to preserve the contents of the box; also to provide a box of this kind which is so made as to enable the cover to be quickly and easily placed in its operative position on the body of the box; also to provide a box of this kind which is inexpensive to manufacture; also to improve the construction of boxes of this kind in other respects hereinafter specified.

In the accompanying drawings:

Figure 1 is an elevation, partly in section, of a box embodying the invention.

Fig. 2 is an elevation thereof showing the cover as it appears when pressure is applied thereto to remove the cover from the box.

Fig. 3 is a top plan view thereof with the cover in the position shown in Fig. 2.

Fig. 4 is a fragmentary sectional elevation thereof on an enlarged scale, showing the cover and body portion of the box separated.

A represents the body portion of a box and B represents the cover. Each of these parts may be formed of sheet metal or other similar material and each part preferably consists of a single, integral piece. The body portion A, as shown in the drawings, is comparatively shallow, but may be made deeper if desired, and consists of a bottom *a* and an integral, annular side wall *a'*. The cover B consists of a substantially flat top portion *b* and an annular rim or flange *b'* which surrounds the upper portion of the wall *a'* of the body portion of the box when the box is closed.

The upper part of the body portion of the

box is slightly turned inwardly or rounded forming a concavo-convex portion as shown at C, and this annular concavo-convex portion is adapted to cooperate with an annular sloping shoulder D on the cover, to form a tight closure. The shoulder D and the concavo-convex portion C are so formed that these two portions have a wedging action when the cover is placed on the body portion, which causes the rounded portion of the body to seat firmly against this shoulder and into the concave portion formed by the junction of the lower part of the shoulder with the wall of the can cover and form a tight joint. To accomplish the best results the concavo-convex portion C is preferably so made that the face C of the body portion will engage the sloping shoulder D while the edge *c* of the body portion of the box extends inwardly out of contact with the shoulder D of the cover, thus producing a better wedging action and a truer fit, and consequently tighter joint than would be produced if the edge *c* of the body portion were depended upon to form a tight joint with the shoulder D, since in stamping the metal the cut edge thereof might not be entirely true. The shoulder D also forms a stop to limit the extent to which the cover B may be forced down upon the can body.

In order to facilitate the removal of the cover from the can body, either the cover or the can body, or both, are so formed that the portion of the cover extending below the shoulder D will be out of contact with the body portion of the can. In the construction shown for this purpose the wall of the can body below the concavo-convex portion C, extends inwardly or is recessed, this being accomplished by pressing the wall of the can body inwardly in such a manner as to form an annular concavity having an upper, gradually inclined portion E which joins the lower part of the concavo-convex or rounded portion C and extends inwardly and downwardly and terminates in a downwardly and outwardly inclining annular shoulder portion E'. The cover B in the construction shown is provided with a substantially vertical annular portion F, which extends downwardly from the lower and outer part of the shouldered stop portion D and the concave portion thereadjacent and the lower part of which may, if desired, be

flared outwardly as indicated at G. As a result of this construction, when the box is closed, the cover and body portion will touch or engage only along the concavo-convex portion C and concave portion and shoulder D, the entire, inwardly, inclined surface E and shoulder E' being out of contact and spaced from the lower portions F and G of the cover flange. Consequently, when it is desired to open the box, this can be easily done by pressing opposite parts of the lower portions of the cover inwardly, for example, by means of the thumb and finger. This pressure results in a contortion or bending of the cover into a shape approximately as shown in Fig. 2, and in full lines in Fig. 3, the dotted lines in Fig. 3 indicating the outline of the cover before the pressure is applied. This change in the shape of the cover loosens the wedged connection between the concavo-convex portion C and the concave portion and shoulder D, and thus loosens the cover from the box so that the cover can easily be lifted off. If desired the cover may be removed by inserting a coin or other flat article between the shoulder E' of the box and the lower edge of the cover and thus forcing the cover upwardly, and the fact that the lower edge of the cover is arranged at a distance from the body of the box greatly facilitates removing the cover in this manner.

The inwardly turned upper edge of the body portion of the box and the lower portion of the cover, which is of considerably greater diameter than the upper edge of the body, also coöperates to facilitate the placing of the cover on the box. This feature is of particular importance from the stand-point of the packer or person filling the boxes. By means of the construction described, in which the inwardly turned upper edge of the body of the box acts to guide the cover into its operative position, an operator can close many more boxes in a period of time than in constructions in which an accurate positioning of the cover on the body of the box is necessary.

The box described is inexpensive to make since the cover described can be made in a single stamping operation and since no opening devices need be attached to the cover or box.

I claim as my invention:

55. 1. In a box, the combination of a single piece body having an annular wall the upper portion of which terminates in an annular concavo-convex portion, and a single piece cover having an annular concave and an inclined portion with which the convex side of said concavo-convex portion of said body is adapted to engage to form a tight joint,

said cover having a portion extending below said concave portion and spaced at a distance from the annular wall of the body, 65 whereby the cover can be disengaged from said body by pressing parts of the downwardly extending portion of said cover toward the body.

2. In a box, the combination of a single 70 piece body having an annular wall the upper portion of which terminates in an annular concavo-convex portion, and with an annular concave portion below said concavo-convex portion, and a cover having an annular inclined and a concave portion with which the convex side of said concavo-convex portion of said body is adapted to engage to form a tight joint, and a portion extending downwardly from said concave portion, said annular concave portion of the body providing a space between said body and said downwardly extending portion of the cover, whereby the cover can be disengaged from said body by pressing parts of 80 said downwardly extending portion of the cover toward said annular concave portion of the body. 85

3. In a box, the combination of a body 90 having an annular concavo-convex upper portion formed by turning inwardly the upper edge of the body, and a cover having an inclined shoulder and a concavo portion there adjacent, said concavo-convex portion of the side wall resting in said concave portion and the upper edge of the body wedging against said shoulder portion to form a tight joint when the cover is placed on the body, said cover having a portion extending below said shoulder portion and spaced from said body, 95 said concavo-convex upper portion also serving to guide a cover into operative relation to the body of the box.

4. In a box, the combination of a single-piece body having an annular wall the upper portion of which terminates in a rounded portion, and a single-piece cover having an outwardly and downwardly inclined portion with which said rounded portion of the body engages to form a tight joint, a substantially vertical annular portion extending downwardly from said inclined portion, and an outwardly flaring annular portion below said vertical annular portion, said outwardly flaring portion providing a space 110 between the lower part of said cover and said body when the cover is in closing position on the body. 115

Witness my hand this 31st day of March, 1920.

CHARLES G. HORNUNG.
